United States Patent

Des. 236,448
Patented Aug. 26, 1975

236,448

BOAT

Urban W. Simon, 1140 S. Raymond Ave., Suite A,
Fullerton, Calif. 92631

Filed July 22, 1974, Ser. No. 490,877

Term of patent 14 years

Int. Cl. D12—06

U.S. Cl. D12—69

FIG. 1

FIG. 2

FIG. 3

FIG. 1 is a top view of a boat embodying the design of my invention;

FIG. 2 is a side elevation view of the boat;

FIG. 3 is a side elevation view of the boat, showing the side opposite to that of FIG. 2;

FIG. 4 is a front elevation view of the boat;

FIG. 5 is a rear elevation view of the boat; and

FIG. 6 is a bottom view of the boat.

I claim:

The ornamental design for a boat, substantially as shown and described.
